UNITED STATES PATENT OFFICE.

HAROLD W. GOFF, OF NEW YORK, N. Y.

CASH TRAY.

Application filed September 18, 1924. Serial No. 738,414.

To all whom it may concern:

Be it known that HAROLD W. GOFF, a citizen of the United States, residing at New York, in the county of New York and State 5 of New York, has invented certain new and useful Improvements in Cash Trays, of which the following is a specification.

This invention relates to a tray or plate particularly adapted for use as a cash tray.

10 It is the object of the present invention to provide a tray of the above mentioned character and one adapted to display an advertisement when a coin is deposited therein, or when a person's hand touches it 15 in withdrawing change therefrom.

20 In accordance with the present invention, the shortcomings of cash trays of the prior art are obviated by the provision of a self-contained and simple device in which purely mechanical means are employed for displaying a normally concealed advertisement. The operation of the device does not depend on an outside source of power, the device 25 may be of the same size and shape as customary cash trays.

25 In accordance with one of the objects of the present invention, an advertising sign normally at rest and preferably, though not necessarily below the surface of the tray, is, 30 upon the application of weight to the tray, suddenly set into motion, e. g., by being pushed above the tray. The moving of an advertising sign or figurine is more likely to 35 attract attention than the sudden illumination of a static sign in an artificially or naturally well-lighted store.

40 In the drawings, Fig. 1 is a perspective view of a cash tray embodying the various features of the present invention; Figs. 2 and 3 are enlarged sectional side views of 45 the tray with the advertising sign in concealed and displayed conditions, respectively; and Fig. 4 is a bottom view of the cash tray.

45 Referring now to the drawings, 1 is a boxlike structure open on its lower side and having in its top a depression 2 serving as a coin-return tray. An advertising sign 3, provided on a sheet of metal or other suitable material is normally concealed from view within the box 1. The sign 3 is in alignment with a slot 4 provided in the top of the box 1 and its upper end projects beyond the top of the box and is bent back at right angles. This bent-back portion is illus-

trated at 5 and may bear any suitable inscription. The lower or free end of the sign 3 is pivotally supported at or near the free end of a lever 6. In the present case, the lever 6 is in the form of an oblong plate, 60 one end of which is provided with slots 9 and 10 through which the ears 7 and 8, projecting from sign 3 may be bent back to hold the sign in place and still permit it a slight rocking motion. The other end of 65 the lever is provided with two fingers 11 and 12 projecting through the side walls of the box 1 and bent down against the box. These will hold the lever 6 in position and still allow a slight rotary movement. Near 70 its inner end the lever 6 is recessed, as shown at 13, and over this recessed portion is hung the bent-back portion apex 14 of a substantially triangular lever 15. The lever 15 is attached at its base to the rear side of box 75 1 by means of ears 16 and 17 projecting therethrough. The ears are bent down parallel with the side walls of the box 1 and extend slightly below the edge of the side wall. Near the end 14 the lever 15 is provided with 80 a hump or projection 18 which also extends below the side walls of the box 1 and is substantially in the same plane as the ends of the ears 16 and 17.

85 The operation of the device will be obvious from the above. When a coin is deposited on the box in the tray 2, or when a person touches the tray in withdrawing the change, then the box is depressed until the forward end 20 touches the top 21 of the 90 counter. Normally, the projection 18 holds the end 20 of the box 1 at a slight distance from the counter, as shown in Fig. 2. In its actuated position (Fig. 3), the lever 15 pushes the lever 6 upwards and the latter, 95 rotating around its pivot points 11 and 12, causes the displaying of the advertisement 3. When the weight is removed from the tray, the advertisement again disappears, being moved down by gravity.

100 It will be obvious to those skilled in the art that the various details of the present structure may be modified without departing from the spirit of the invention defined in the claims. The manner in which the 105 levers 6 and 15 are interconnected is, to a certain extent, arbitrary, and depends on the size of the device or the amount of pressure that is required to cause the displaying 110 of the advertisement. The advertising

sign may, of course, be caused to appear and disappear or perform any other movement to attract attention.

What I claim is:

- 5 1. In combination, a cash tray, an advertising sign normally concealed from sight by the surface of said tray, and mechanism responsive to weight applied to said tray for lifting said sign into view above the 10 surface of said tray.
- 15 2. In combination, a cash tray, an advertising sign normally concealed from sight by said tray, and a lever for displaying said sign upon the application of weight to said tray.
- 20 3. In combination, a box open on one side, the top of said box serving as a cash tray, a slot in the top of said box, an advertising sign within said box and in alignment with said slot, a lever carrying said sign, and means responsive to the application of weight to said tray for operating said lever to lift said sign through said tray.
- 25 4. In combination, a box open on one side, the top of said box serving as a cash tray, a slot in the top of said box, an advertising sign within said box and in alignment with said slot, a lever having one end movably attached to a side wall of said box and 30 carrying at its other end said sign, a sec-

ond lever having one end movably attached to an opposite wall of said box and the other end to said first mentioned lever intermediate the ends thereof, and a projection on said second lever on which the 35 box normally rests.

5. In combination, a box open on one side, the top of said box serving as a cash tray and provided with a slot, an advertising sign within said box, the end of said sign 40 projecting through said slot and being bent back in alignment with the top of the box, a lever having one end rotatably attached to a side wall of said box and rotatably supporting at its other end said sign, a substantially triangular lever movably attached at its apex to said first mentioned lever intermediate the ends thereof, two ears projecting from the base of said triangular lever through apertures in the opposite side 45 wall of said box and bent down parallel with the side wall and beyond the edge thereof, and a projection on said triangular lever near its apex in substantially one plane with the ends of said ears and serving therewith as a rest for the box.

In testimony whereof, I have signed my name to this specification, this 17th day of September, 1924.

HAROLD W. GOFF.
